CAN DEPALLETIZING MACHINE

Earl E. Jeremiah, Los Altos, Calif., assignor to National Can Corporation, Chicago, Ill., a corporation of Delaware

Filed June 28, 1962, Ser. No. 206,090

1 Claim. (Cl. 214—8.5)

This invention relates to a new and improved machine for removing cans from pallets. At the present, transportation of cans on pallets is becoming increasingly popular. An ordinary pallet such as that used in conjunction with fork-lift trucks is covered with a layer of cans having their axes upright and a spacer consisting of a sheet of cardboard or the like is placed over the bottommost layer. Thereupon, succeeding layers of cans are superimposed until the desired height is reached. A covering of cardboard or paper or the like is applied around the cans on the pallet to protect them until the pallet is unloaded. The present invention relates to a machine which unloads the cans from the pallet. This application is a continuation-in-part of my co-pending application Serial No. 856,135, filed November 30, 1959.

One of the features and advantages of the present machine is the fact that damage to the cans is avoided in that the cans are removed from the pallet, layer by layer, in a regular manner so that the likelihood of crushing or denting the cans is minimized.

Another feature of the invention is the fact that it operates at a very high speed so that pallets may be unloaded and fed into a can filling machine at a cannery at least as fast as the rate of operation of the filling machine, and thus the speed of the cannery line is not slowed by the use of the present invention.

A still further feature of the invention is the fact that it is adjustable for cans of different heights so that a single machine may be used to handle cans of a variety of different sizes. In this connection, a further feature of the invention is the fact that the can diameter is relatively unimportant to the operation of the machine.

Another important advantage of the present invention is the fact that manual operation and hence labor costs are reduced over conventional methods of handling cans preparatory to filling.

Other objects of the present invention will become apparent upon reading the following specification and referring to the accompanying drawings in which similar characters of reference represent corresponding parts in each of the several views.

In the drawings:

FIG. 1 is a side elevation of the machine.

FIG. 2 is a top plan thereof.

FIG. 3 is a sectional view taken substantially along the line 3—3 of FIG. 2.

FIG. 4 is an enlarged fragmentary sectional view taken substantially along line 4—4 of FIG. 1.

FIG. 5 is a side elevational view of a pallet of cans, prior to being unloaded by the machine which is the subject of this invention.

The present invention is used to handle cans 12 which are stacked with their axes vertical on a conventional pallet 11 which consists of a horizontal platform 13 and depending legs 14 which are vertically disposed and spaced apart to accommodate the forks of a conventional lift-truck. In accordance with this invention, layers of cans 12 are positioned on the platform 13 arranged in rows, alternate rows being preferably staggered to permit a larger number of cans to be placed in a given cross-sectional area of pallet. On top of each layer of cans is positioned a separator 16 of cardboard or the like which separates the adjacent layers of cans. The number of layers of cans is variable depending upon the size thereof.

2

The machine which is the subject of the present invention consists of three stations, a pallet transfer station A, a pallet elevating station B, and a can unloading station C.

5 Preferably, the various stations of the machine are supported by a common frame which may be moved from place to place in a cannery. For such purpose, the frame consists of a horizontal base member 21, central vertical members 22 which are interconnected at the tops by longitudinal and transverse connecting members 23 and 24, respectively, and front and rear support legs 26 and 27, respectively.

The pallet transfer station A consists of an elongated horizontally disposed chain 31 on either side of the machine, which is supported by longitudinal horizontal chain guide 32 which extends the length of the machine on either side thereof and the guides 32 are interconnected by transverse connecting members 33 at intervals along the length thereof to form a rigid structure holding the chains 31 parallel.

15 Guides 32 are supported by the legs 26. At the rearward end of guide 32 is a transverse horizontal drive shaft 33 which carries drive sprockets 34 for chains 31. At the forward end of guide 32 is a transverse idler shaft 36 having idler sprockets 37, and the chains 31 pass around the sprockets 34 and 37. Shaft 33 is driven from electric motor 38 by means of sprockets 39 and 41 on the motor shaft and drive shaft 33, respectively, which are interconnected by chain 42. Starting and stopping of motor 25 38 is controlled by button 43 on control box 44 which is located at a convenient position so that the operator can control the movement of chains 31. The filled pallet 11 is positioned on top of the chains 31 at the forward end of the machine and advanced from the loading station indicated by reference numeral 46 into the pallet elevator station B. While the pallet is being unloaded at the can unloading station C immediately above the elevator station B, the next pallet in order is being placed in position at loading station 46. After the cans have been removed 30 from the pallet at station C, the pallet is lowered by elevator station B back to the level of the chains 31. Thereupon, when the operator next presses the button 43, motor 38 moves chains 31 ahead so that the unloaded pallet is moved off the front of the machine at the same time that 35 the next full pallet is moving into position in the elevator station B.

30 Elevator station B consists of a pair of vertical sides 51 on either side of the machine which are spaced apart a distance slightly greater than the widths of the pallet. 50 Likewise, located on either side of the machine is a pair of vertical chain guides 52, each of which has at its bottom end a transverse drive shaft 53 which extends across the width of the machine and at its upper end a stub idler shaft 54.

55 Shafts 53 and 54 carry drive and driven sprockets 56 and 57, respectively, carrying elevator chains 58. There are four chains 58, one at each corner of the elevator station. Shafts 53 are interconnected by means of horizontal connecting chain 59 which interconnects sprockets 60 61 on the right-hand ends of shafts 53. One of the shafts 53 also carries a sprocket 62 which is driven from motor 63 by means of sprocket 64 on motor shaft and chain 66. Each chain 58 has fastened thereto a lifter plate 67 which projects inwardly of the machine through a slot 68 in side 51. The inner ends of plate 67 on either side are connected by horizontal longitudinal pallet lifting bar 69, which fits under the outside edge of the pallet. Each plate 67 has a pair of rollers 65 which fit in grooves 70 in vertically disposed trackways 70a adjacent the path of 65 movement of plate 67. Motor 63 is controlled by button 71 on control box 44 and by pressing button 71 the chains 58 are caused to move to raise the lifter bar 69.

and elevate the pallet until the uppermost cans contact finger 72 which projects outwardly into the machine and is connected to switch 73 which stops the movement of chains 58 when the cans have risen to the proper height. As each layer of cans is stripped off the pallet by means which is hereinafter described, the pallet is raised in increments until the topmost can contacts the fingers 72 whereupon the pallet is held stationary until the next layer can be swept off. After all of the layers of cans are removed from the pallet, the pallet engages a reversing switch (not shown) which turns reversible motor 63 in the opposite direction and lowers the pallet to the level of the chains 31 whereupon the elevator cycle is repeated.

The can unloading station C is located on top of the elevator station B. For such purpose, there is located extending transversely horizontally of the machine at the front thereof a drive shaft 81, and at the rear of the station and upper and a lower transverse horizontal idler shafts 82, 83. On either side of the machine located on shafts 81, 82, 83 are drive sprockets 84 and driven sprockets 86, 87, around which pass chain 88 on either side of the machine. The distance between shafts 81 and shafts 82, 83 is greater than the length of the pallet 11. Shaft 81 is driven from motor 91 by means of sprocket 92 on the shaft of motor 91, chain 93 and sprocket 94 on shaft 81. Motor 91 is controlled by push button switch 96 on control panel box 44. Extending transversely across and interconnecting chains 88 are sweeper bars 97. The function of sweeper bars 97 is to move around behind the last row of cans on the pallet 11 and push the cans rearward off of the pallet.

Located rearwardly in the machine is a lower guide plate 101 which extends horizontally for a short distance beyond the elevator station B in a stretch indicated by reference numeral 101, and then curved at a radial section 102 and then merges into a vertically downwardly disposed section 103. Substantially parallel to the aforementioned plate is an upper guide plate 104 which has an upper radial section 104 generally parallel to section 102 and spaced therefrom a distance equal to the height of the can being handled, and then merges into a vertically downward section 106 parallel to station 103. The guides 104, 106 are held a predetermined distance from guide 102, 103 by means of adjustable bracket arms 107 having threaded portion 108 and nuts 109 thereon. By moving the nuts 109 along the threaded portions 108, the distance of member 104, 106 from member 102, 103 may be adjusted to accommodate different can heights.

The entire can guide system is termed a cascade 111 which guides the cans as they are pushed off the pallet, first horizontally rearwardly and then turns them to a position where the axes are horizontal instead of vertical and extend longitudinally of the machine. Upper and lower rods 112, 113 on either end of the cascade 111 engage the cans on either side of the pallet layer and prevent the cans from escaping from the cascade. The cascade portion is supported by horizontal arms 114 which extend rearwardly from rearmost legs 22 and are supported by legs 27.

At the bottom of cascade 111 is a horizontal belt 116 which passes around drive pulley 117 and idler pulley 118. The axes of pulleys 117 and 118 are horizontal and extend longitudinally of the machine, the drive pulley 117 being on the left-hand side immediately beneath the cascade 111 and the driven pulley 118 on the right-hand side. Pulley 117 is driven from electric motor 119 through belt 121. Thus, the cans when they reach the bottom of the layer 111 come in contact with belt 116 which moves the cans toward the side of the machine where they are

picked up by a takeaway conveyor 126, can elevator (not shown) or other conveyor.

In operation, pallets are deposited at the front of the machine on top of chains 31, as indicated in the pallet loading zone reference numeral 46. When the prior pallet has been emptied, the operator presses button 43 which moves the previous pallet out toward the rear of the machine where it is discharged and moves the full pallet toward the elevator station B. When the pallet is in proper position, the chains 31 are stopped. Thereupon, the operator pushes button 71 which causes the lifter member 67 on chains 58 to raise the pallet until the uppermost can contacts the switch finger 72 which stops movement of the pallet.

Thereupon, the operator presses button 96 which causes sweeper bars 97 to sweep the top layer of cans rearwardly of the machine onto the cascade 111 whence they slide down to the bottom and come in contact with belt 116 and are moved sideways of the machine and thence away from the machine. After the top layer of cans has been swept from the pallet, an automatic relay circuit and limit switches not herein illustrated but which will be understood by one skilled in the art stops the chains 88 and causes the pallet to be raised until the next layer of cans contacts finger 72. Thereupon, chains 88 are again started and the next sweeper bar 97 sweeps the second layer of cans off the pallet. The separators 16 between the layers of cans are lifted away as each layer of cans is swept off the pallet and from time to time the collection of separators may be removed by the operator for return to the can factory and subsequent use.

What is claimed is:

In a can depalletizing machine, an elevator to raise vertically a pallet of cans having their axes vertical, comprising a plurality of vertical trackways on opposite sides of said machine, said trackways being formed with grooves extending vertically the height of said elevator, a plurality of plates, at least two rollers connected to each said plate and sliding in said grooves in one of said trackways, horizontal members on each side of said machine fixed to the inner ends of at least two said plates, said horizontal members being positioned to engage under the opposite outer edges of said pallet, first means for raising said plates in increments equal to the height of one can, a pusher bar, second means for moving said pusher bar horizontally across the topmost layer of cans on said elevator, a cascade guide having top and bottom layers spaced apart the height of a can and curving from a horizontal stretch adjacent the top of said elevator downwardly to below said elevator, and electrical control means to de-energize said first means and energize said second means when a layer of cans has been raised by said elevator to the level of said horizontal stretch and to de-energize said second means and energize said first means when each topmost layer of cans has been pushed into said guide by said pusher bar.
